UNITED STATES PATENT OFFICE.

CHARLES W. JACKMAN, OF DETROIT, MICHIGAN, ASSIGNOR OF ONE-HALF TO MILES M. JACKMAN, OF DETROIT, MICHIGAN.

ROTARY PUMP.

1,395,114.

Specification of Letters Patent.

Patented Oct. 25, 1921.

Application filed August 11, 1919. Serial No. 318,589.

To all whom it may concern:

Be it known that I, CHARLES W. JACKMAN, a citizen of the United States, residing at Detroit, in the county of Wayne and State of Michigan, have invented certain new and useful Improvements in a Rotary Pump, of which the following is a specification.

This invention relates to the class of rotary pumps of the radial flow type, and has for one of its objects to simplify the construction and increase the efficiency and utility of devices of this character.

Another object of this invention is to produce a pump of this character which may be readily and quickly reversed without disassembling or changing any of the parts.

Another object of the invention is to provide a pump of this character in which the parts remain unchanged when the pump is operated in either direction.

With these and other objects in view the invention consists in certain novel features of construction as hereafter shown and described and then specifically pointed out in the claim, and in the drawings illustrative of the preferred embodiment of the invention,

Figure 1 is a side elevation of the improved pump.

Fig. 2 is a sectional side elevation.

Fig. 3 is a sectional detail illustrating the operation of the rotor and abutment.

Fig. 4 is a detached perspective view of one of the abutments.

Fig. 5 is a detached perspective view of one of the ring gears for operating the abutment.

Fig. 6 is an end elevation.

Fig. 7 is a vertical section on the line 7-7 of Fig. 1 looking in the direction of the arrow.

Fig. 8 is a side view of the rotor.

Fig. 9 is a plan view of the rotor.

Fig. 10 is a detail view illustrating a modification in the manner of operating the abutments.

Fig. 11 is a detached perspective view of one of the combined glands, packing and gear centering members.

The improved pump comprises a drum or body 10 closed at one side and provided at the other side with a closure 11 extending over the open side. Protruding from the

drum at uniform distances are chambers 12, 55 the chambers being closed at one end and open at the other end, with the centers of the chambers preferably at the inner peripheral line of the bore of the drum, as indicated in Fig. 2. Any required number of 60 the chambers 12 may be employed but for the purpose of illustration four are shown. Formed on the body of the drum 10 at each side of the chambers 12 are bosses 13 tapped to receive attaching bolts, and the closure 11 65 is provided with enlargements having openings corresponding to and registering with the open sides of the chambers and providing access to the chambers.

Mounted for oscillation in each of the 70 chambers 12 is an abutment member, each abutment comprising a supporting disk 18 fitting in a seat 19 in the closed wall of the chamber and from which a stud 17 extends.

The body portion of each abutment is 75 semi cylindrical in outline as shown at 20 in Fig. 4 and with a semi-circular closure 21 at the other end.

Protruding from the closed side of the chamber 12 are bosses 15 one for each chamber, and bored to receive wear bushings 16, the latter constituting bearings for the studs 17 of the abutment which are thus mounted for rotation in the chambers.

Protruding from the half closure 21 is a 85 hub 22 over which an annular or ring gear 23 fits and is held from rotation thereon by a key engaging in keyways in the hub members. Protruding from the hub 22 is a stud 24 corresponding to the stud 17 and in alignment therewith.

Bearing upon the closure 11 and extending over each of the openings therein is a glandlike device 25 having projections at the ends to receive attaching cap screws 26 95 tapped into the bosses 13. Each gland 25 is bored to receive one of the studs 24, the bore being preferably provided with a wear bushing 27 as shown.

Projecting inwardly from each gland 25 100 is a filler member 28 which closely engage in the openings in the closures 11 and operate as packings to prevent leakage, as well as to "center" the glands.

Projecting from the closed side of the 105 drum 10 is a relatively large chamber 29 while a similar chamber 30 projects from the closure 11.

The chamber 29 is provided with a threaded opening to receive a pipe 31 while the chamber 30 is provided with a threaded opening to receive a similar pipe 32.

5 When the pump is operated in one direction the pipe 32 is the intake while the pipe 31 is the outlet, and when the pump is operated in the other direction the pipe 31 becomes the intake and the pipe 32 the 10 outlet.

The chamber 30 communicates with the interior of the drum 10 through the closure 11 while the chamber 29 communicates with the interior of the drum 10 through the rear 15 wall of the latter.

The chambers 29 and 30 are provided respectively with bearings 33 and 34 suitably packed, to support the main drive shaft 35.

Mounted within the drum 10 upon the 20 shaft 35 and rotative therewith, is a rotor or piston element and including a central hollow shell or body portion 36 a hub portion 37 and oppositely directed wing or branch portions 38. The outer faces 38' of 25 the wing portions 38 are curved to engage the inner face of the drum 10 and are wider than the inwardly opening portions of the chambers 12, so that they consecutively close the openings of the chambers and extend beyond 30 their side edges as they pass them during the rotation of the piston or rotor.

The body portion 36 of the rotor and the wing portions 38 are hollow and communicate with each other, while the hub portion 37 extends entirely through the body portion and beyond its side faces and bears at the outer ends against stop collars, indicated at 39 on the shaft 35.

Extending between the hub 37 and the 40 outer drum engaging ends of the wings 38 are partitions 40—41.

The opposite sides of the body portion 36 between the wing portions 38 are segmental in outline, as shown at 38', and located within 45 in the body portion and extending between the segmental portions and the parts of the hub within the body and the parts of the partitions 40 and 41 within the body, are other partitions 42 and 43 the latter being 50 arranged reversely oblique, as indicated by dotted lines in Fig. 9.

The body portion 36 of the piston or rotor is formed with side openings indicated at 44 and 45 the opening 44 being surrounded 55 by an annular flange 46 to support a ring gear 47.

The partition 42 provides communication between the interior of one of the wings 38 and the side opening 44, while the partition 60 43 provides communication between the interior of the other wing 38 and the other side opening 45.

When the parts are assembled the smaller ring gears 23 are in constant engagement 65 with the larger ring gear 47 so that when

the piston is rotated by power applied to the shaft 35, the abutments 18—20—21 will be correspondingly rotated.

The gears will be so proportioned that when the ends 38' of the wings 38 of the 70 piston are passing the abutments, the portions 20 of two of the latter will be turned outwardly within the chambers 12 while the solid portions 20 of the other two abutments will be turned inwardly in engagement with 75 the imperforate segmental peripheries of the piston body, 36, as shown in Fig. 2. By this means the portions 20 of two of the abutments are moved out of the way of the moving wings of the piston, while the solid 80 portions of the other two abutments are caused to roll water tight against the segmental portions of the body 36.

By this means closed pockets are consecutively formed within the drum 10 as the 85 piston is rotated.

As the piston is rotated in one direction the water or the liquid flowing through the intake conductor 32 is caught in the hollow wings 38 alternately and continuously and 90 forcibly discharged through the outlet conductor 31, thus producing the desirable continuous radial flow of the liquid.

By reversing the motion of the shaft 35 the direction of flow will be reversed, as will 95 be obvious, without changing any of the parts.

The improved apparatus is simple in construction and can be inexpensively manufactured as the drum 10, the chambers 12, the 100 seats 19 can be "machined" with the minimum of labor, while the piston or rotor member may be likewise "machined."

The arrangement of parts enables suitable packing elements to be disposed between the 105 working parts and thus insures liquid tight joints and prevents leakage.

The arrangement shown so balances the parts that pulsations are practically obviated, due to the manner in which the piston 110 or rotor and the abutments coöperate.

The arrangement shown is the preferable one, but it is not desired to limit the construction or the arrangement of parts to those shown, as modifications within the 115 scope of the claim may be made without departing from the principle of the invention, or sacrificing any of its advantages.

In Fig. 10 a modification in the construction is shown consisting in extending the 120 shaft 35 and the studs 17 beyond the closed rear side 11 of the shell and supplying the extended portion of the shaft 35 with a master gear 48 and the extended studs 17 with pinions 49, as shown in Fig. 10. This 125 arrangement dispenses with the annular support 46, and the ring gears 23 and 47 and substitutes the gears 48 and 49 therefor.

What I claim:

A pump including a casing having a plu- 130

rality of chambers in spaced relation and opening into the casing, an abutment rotative in each chamber and each abutment having an unobstructed interior and including a 5 segmental portion projecting into the casing when the abutment is in one position, a rotor comprising a cylindrical central portion having openings in the ends with projections extending laterally from the ends, the projections being connected by continuous segmental portions conforming to the interior 10 of the casing and of greater width than the

entrances of the chambers so that they bridge the openings and extend beyond the edges of the same when in one position to cut off the 15 passage for a period of time at each revolution of the rotor and said segmental portions operating against the interior of the casing and the cylindrical central portion rolling upon the segmental portion of the 20 abutment when in another position.

In testimony whereof I affix my signature hereto.

CHARLES W. JACKMAN.
